(57) **CLAIM**

The ornamental design for an applicator nozzle, as shown and described.

DESCRIPTION

FIG. 1 is a top perspective view of an applicator nozzle, showing our new design.

FIG. 2 is a side view of the applicator nozzle;

FIG. 3 is a bottom perspective view of the applicator nozzle;

FIG. 4 is a first end view of the applicator nozzle;

FIG. 5 is a second end view of the applicator nozzle;

FIG. 6 is a bottom view of the applicator nozzle; and,

FIG. 7 is a top view of the applicator nozzle.

The broken lines illustrate portions of the applicator nozzle that form no part of the claimed design. The dashed circular broken line in FIG. 7 defines a boundary of the claimed design within which no subject matter is claimed.
